Primary Examiner — Darlington Ly(74) *Attorney, Agent, or Firm* — Womble Carlyle Sandridge & Rice LLP(57) **CLAIM**

The ornamental design for a front bumper for a vehicle, as shown and described.

DESCRIPTION

FIG. 1 is a perspective view of a front bumper for a vehicle showing our new design.

FIG. 2 is a front view thereof.

FIG. 3 is a back view thereof.

FIG. 4 is a top view thereof.

FIG. 5 is a bottom view thereof.

FIG. 6 is a left side view thereof; and,

FIG. 7 is a right side view thereof.

The broken lines illustrate portions of the front bumper for a vehicle that form no part of the claimed design.

1 Claim, 5 Drawing Sheets(56)
